STAPLING MACHINE

Werner Schafroth, Herrin, Ill.

Application January 17, 1956, Serial No. 39,816

Term of patent 14 years

(Cl. D74—1)

FIG.1.

FIG.2.

FIG.3.

FIG.5.

FIG.4.

Fig. 1 is a side perspective view of a stapling machine, showing my new design;

Fig. 2 is a front elevational view thereof;

Fig. 3 is a rear elevational view;

Fig. 4 is a top plan view thereof as it appears with the operating lever in lowered operating position; and

Fig. 5 is a side elevational view thereof.

The essential features of my design reside in the portions shown in solid lines on the drawing.

I claim:

The ornamental design for a stapling machine, substantially as shown and described.
